COMBINED CHECKER AND CHESSBOARD

David Aiuppa, W207 S8286 Hillendale Drive,
Muskego, Wis. 53150

Filed Aug. 16, 1971, Ser. No. 172,368

Term of patent 14 years

Int. Cl. D21—01

U.S. Cl. D34—5 SS

FIG. 1 is a top plan view of the combined checker and chessboard showing my new design; the opposite side of the checker and chessboard is plain.

FIG. 2 is an end view of the checker and chessboard. I claim:

The ornamental design for a combined checker and chessboard, as shown and described.
